UNITED STATES PATENT OFFICE.

FRANK B. BELL, OF PITTSBURGH, PENNSYLVANIA, ASSIGNOR TO EDGEWATER STEEL COMPANY, OF PITTSBURGH, PENNSYLVANIA, A CORPORATION OF PENNSYLVANIA.

APPARATUS FOR REMOVING ARTICLES FROM FORGING DIES OR THE LIKE.

Application filed June 11, 1920. Serial No. 388,123.

To all whom it may concern:

Be it known that I, FRANK B. BELL, a citizen of the United States, residing in Pittsburgh, in the county of Allegheny and

- 5 State of Pennsylvania, have invented a new and useful Improvement in Apparatus for Removing Articles from Forging Dies or the like, of which the following is a specification.
- 10 This invention relates in general to the art of forming metal articles, and more particularly to heavy articles, such as car wheels and the like, pressed or otherwise formed in the molds.

- 15 The invention has for its object broadly the facilitating of the removing of the metal articles, after forming, from the molds in which they have received their shape. While the invention has more particular reference, particularly in the forms selected for illustration, to the manufacture of forged car wheel blanks, it will be readily manifest that it has other and more general application.

- 20 25 In the pressing of car wheels, which is selected as an example of a valuable use of the invention, the procedure is as follows: A short ingot block is provided, this block is upset and a hole is punched in its center and the block is then dropped upon a forming die in the center of which is provided an upwardly projecting mandrel. A top forming die is then brought down with sufficient pressure to form the hub and shape 30 35 the car wheel. I have found that this forging of the blank around the mandrel causes it to grip the mandrel tightly and my invention in this connection is employed to free the whole or partly formed car wheel or article from the mandrel and permit it to be gripped by the tongs and removed.

- 40 The invention has for an important object the provision of simple and effective means for freeing the formed article from the mold 45 in or about which it has been formed.

- Another object of the invention is the provision of means for accomplishing this result, which will be wholly automatic in its action and which will not require the provision of complicated or delicate parts likely to require frequent adjustment, repair or replacement. In this connection it is to

be noted that the invention is usable with the forging or pressing of heavy articles in connection with presses acting with great 55 force.

Another important object of the invention is the provision of means for facilitating removing of the formed articles from the molds in which they have been formed by 60 a press, without requiring that the press be idle during the article removing operation.

Another important object of the invention is the provision of such a construction 65 having these and other advantages, which will not require manipulation by attendants or operators or other attention during the operations of the apparatus of which it forms a part.

70 Numerous other objects and advantages of the invention will be apparent as it is better understood from the following description, which taken in connection with the accompanying drawings discloses a preferred embodiment thereof.

75 Referring to the drawing,

Figure 1 is a section through the posts or supports of a press showing an embodiment of my invention in operative relation with 80 the press bed;

Fig. 2 is a side elevation thereof showing the arrangement of the parts just before the freeing of the formed article;

Fig. 3 is a similar view showing the arrangement after the article is lifted;

Fig. 4 is an enlarged top plan view of the mold, the mandrel being shown in section;

Fig. 5 is a section taken substantially on the line 5—5 of Fig. 4;

Fig. 6 is a perspective view of one of the side filler blocks;

Fig. 7 is a perspective view of one of the article lifting members; and

Fig. 8 is a perspective view of one of the inner filler blocks.

For the purpose of illustrating my invention I have shown on the drawing a press bed 11 movable in any suitable or usual fashion on press bed tracks 12 so that it moves back and forth beneath the operative parts of a press of any preferred character. Since the details of this press construction form no part of my present invention I have

merely shown on the drawing the four uprights or supports 13 carrying the operative parts.

The press bed is provided with a plurality 5 of operating stations, four in the present instance, and indicated at 14, 15, 16 and 17, the station 17 being provided with a mold for forming the hub and shaping the car wheel. The details of operations occurring 10 at the stations 14 and 15 are unimportant to the present invention, it being sufficient to say that at these stations preliminary formations are given to the blank—as upsetting and punching it, etc. The mold located at 15 the station 17 is indicated by reference character 18 and this mold is shown in Figs. 4 to 8. It comprises a body 21 carrying, preferably, a mandrel 22 about which the car wheel is wholly or partly formed, it being 20 understood that the co-operating die or mold (not shown on the drawing) is provided in the press and is forced down to give formation to the article. As has been stated, this formation of the article about the mandrel 25 causes it to grip the mandrel tightly and notwithstanding the usual tapering form given these mandrels difficulty has been experienced in removing the wholly or partly formed car wheel. I provide adjacent opposite 30 site sides of the mold recesses 23 extending into the upper mold face and to receive the head 24 of lifters or ejectors as shown in Fig. 7, filler blocks 20 being provided in the recess behind the heads of the lifters. An 35 opening 25 extends down from each recess 23 into a slot 26, which extends through the mold and has a tapered opening 27 at the side of the mold adjacent the end of the press bed or table 11.

40 Each slot 26 as formed extends through the side of the mold and is closed at the side by a filler block 28 having a flange 29 seated in a recess 31 in the portion beneath the slot and held in place at the top by a 45 set screw 33 engaging threads formed partly in the mold body and partly in the filler block and provided after the filler block has been arranged in assembled position. Each article lifter is provided with a tail or stem 50 34 extending down into the slot 26 and behind the filler block and provided with a bevelled end 35. These stems are adapted to be engaged by means located in the path of travel of the mold as the table reaches the 55 right-hand end of its travel, viewing Figs. 1 to 3 of drawing, which lift the lifters and free the article indicated at 36 from the mandrel 22.

In the present instance this means consists 60 of a pair of wedges 37 fixed in holders 38 mounted in a support 39 held upon the end of the bed support 12. As will be seen from Figs. 1 to 3 these wedges are mounted to be 65 projected into the slots 26 upon movement of the press table or bed from the position

shown in Fig. 2 to that shown in Fig. 3 and moving through the slots are interposed beneath the stems 34 of the lifters forcing the car wheel up, as seen in Fig. 3 so that it may be engaged by the tongs of the crane 70 (not shown on the drawing).

This lifting means is wholly automatic in its action and the lifting operation occurs without interruption to the work of the press and while the bed is arranged to permit the 75 press to perform other operations upon a succeeding blank.

It is thought that the invention and many of its attendant advantages will be understood from the foregoing description, and it 80 will be apparent that various changes may be made in the form, construction and arrangement of the parts without departing from the spirit and scope of the invention, or sacrificing all of its material advantages, 85 the form hereinbefore described being merely a preferred embodiment thereof.

I claim:

1. In an apparatus of the general character described, the combination of a unitary mold employed in the forming of an article, and means insertible laterally in the mold and beneath the article for freeing it of the mold.

2. In an apparatus of the general character described, the combination of a unitary mold employed in the forming of an article, and wedges insertible in the mold and beneath the article for freeing it of the mold.

3. In an apparatus of the general character described, the combination of a mold having a central fixed mandrel employed in the forming of an article and having parts liftable to lift the article from said mandrel, and wedging means adapted to enter the mold to lift said parts.

4. In an apparatus of the general character described, the combination of a unitary mold employed in the forming of an article and having parts located in the mold and adapted to be lifted to free the article from the mold, and wedging means insertible in the side of the mold for lifting said parts.

5. In an apparatus of the general character described, the combination of a unitary mold employed in the formation of an article, and wedging means insertible through the side of the mold for lifting the article 120 to free it from the mold.

6. In an apparatus of the general character described, the combination of a mold employed in the formation of an article, said mold mounted for sidewise movement, 125 and means positioned in the path of said mold for freeing articles formed thereby.

7. In an apparatus of the general character described, the combination of a mold employed in the formation of an article, 130

said mold mounted for sidewise movement, and means engaging the mold in its sidewise movement to lift articles formed in and free them from said mold.

8. In an apparatus of the general character described, the combination of a reciprocating mold support, a mold carried thereby, and means insertible laterally beneath the article for lifting the article upon reciprocation of said support and freeing it from the mold.

9. In an apparatus of the general character described, the combination of a mold support having lateral reciprocation, a mold carried thereby, and means insertible in the mold in its lateral reciprocation for freeing articles formed thereby.

10. In an apparatus of the general character described, the combination of a mold, a press bed movable laterally, and means rendered operable by movement of said press bed for freeing articles formed by said mold.

11. In an apparatus of the general character described, the combination of a press bed having a plurality of operative stations, and mounted for sidewise movement, a mold carried by said bed, and means lo-

cated and adjacent to and operable through the movement of the press bed for freeing articles pressed in said mold.

12. In an apparatus of the general character described, the combination of a press bed, a mold on said press bed and having a liftable bottom, and means insertible beneath said bottom in the movement of said press bed for lifting said bottom above said press bed to free articles formed by the mold.

13. In an apparatus of the general character described, the combination of a reciprocating press bed, a mold carried by said press, fixed means located over the end of the bed at the end of the travel of said end for lifting and freeing articles formed by said mold.

14. In an apparatus of the general character described, the combination of a reciprocating press bed, a mold carried thereby, wedge members located in fixed position at an end of the travel of said press bed and in position to extend over the press bed and to engage in said mold to lift and free articles formed by said mold.

FRANK B. BELL.
